OLIVER S. WRIGHT, OF MASONTOWN, PENNSYLVANIA, ASSIGNOR TO NEPTUNE MANUFACTURING COMPANY, OF MASONTOWN, PENNSYLVANIA, A CORPORATION OF DELAWARE.

HAIR-WAVING DEVICE.

Application filed November 21, 1925. Serial No. 70,476.

This invention relates to hair waving devices or implements for producing Marcel waves and it has more particular reference to appliances which may be electrically heated by connection with an ordinary electric light socket and manipulation to produce esthetic and attractive coiffures.

One object of this invention is to provide a hair waving device characterized by 10 toothed gripping members that conform to the curvature of the head and which will fashion smoother waves than has hitherto been possible with devices of analogous character.

15 Another object is the provision of a novel type of hair waver which is automatically reciprocated or shogged by the users one hand over an arcuate course contingent upon the proper pressures normally applied in 20 gripping the device in the hair under treatment, in contra-distinction with the necessity of employing both hands when using known devices of analogous character.

A further object of the present improvements is to provide a novel type of hair waving implement capable of applying different "heats" to the hair whereby waves of 25 varied degree and permanence are readily produced.

30 A still further object of the invention is to furnish a hair waving implement which may be freely used without producing the unsightly ridges and "kinks" commonly associated with prevailing methods at present in vogue in the hairdressing arts.

With the foregoing and other objects in view, which will be apparent from the following detailed description of one practical embodiment of this invention, the same 40 may be tersely stated as embracing certain structural features, combinations and arrangements of parts, hereinafter set forth, illustrated by the accompanying sheets of drawings, and succinctly defined as to character and scope in the subjoined claims.

45 In the drawings:—

Fig. I, is a plan view of my novel hair waving implement in one of its closed positions, with fragmentary portions removed 50 to clearly illustrate a pivotal connection later on fully described.

Fig. II, is a side elevation of the preceding view with parts broken away or in

section to better illustrate certain underlying features.

55 Fig. III, is a cross-sectional view taken as indicated by the arrows III—III in Fig. II, and showing the manner in which hair is held between the opposed gripping members.

60 Fig. IV, is a similar side elevation to Fig. II but illustrating the relative positions occupied by the respective operative members under gripping pressure applied to the handles; or, when the heating element jaw is "shogged" relative to the forked element in one direction, as later on explained.

65 Fig. V, is a side elevation of the device showing the position occupied by the several parts when the gripping pressure is released from the handles after collapse as illustrated by the preceding view.

70 Fig. VI, is a top plan view of Fig. V, with some strands of hair held between the gripping members to illustrate a certain 75 phase of the invention.

Fig. VII, is a part end view taken on the line VII—VII on Fig. II to illustrate the heater terminal connections.

80 Fig. VIII, is an end view of the connector plug; and,

Fig. IX, is a conventional diagram of the heater wiring.

85 According to the construction shown, my novel hair waving device comprises a main gripping member comprehensively designated by the index numeral 9, and a companion forked gripping member similarly indicated by the symbol 10, both constructed of metal high in thermal conductivity. These members 9, 10 are connected together with capacity for pivotal and relative "shogging" movement through the medium of a shouldered stud 11, conveniently screw-threaded into the member 10 with a non-threaded shank portion 12 engaging a slot 13 in the member 9; whereas a jam nut 14 serves to retain the respective parts in operative relation. Suitable handles or grasps 15, 16 of heat insulating material, are applied to the respective members 9, 10 so as to protect the hands of the user.

90 The main gripping member 9, it is to be particularly observed, is longitudinally curved and characterized by a similarly-extending central raised portion 17 with co-

75

80

85

90

95

100

105

extensive troughed flanges 18, 18 merging into said raised portion. The raised portion 17 is made hollow to accommodate an electric heating element 19—conveniently of the 5 three wire resistance type—comprising a coil 20 embedded in a suitable di-electric configured in cross-section to snugly fit said raised portion, and retained against displacement by a closure plate 21, removably 10 attached in position by countersink screws 22—Fig. III. Terminal pins 23, afford coupling means for the connector plug 24 having a conventional cable 25 for conduction of electrical energy from any convenient 15 source, and one of said pins 23 is fitted with a spring contact 26 co-operative, as later on explained, with a screw stud 27 connecting with a heater shunt or tap—later on again referred to—when the plug 24 is placed in 20 one position, and when said plug is reversed it snaps back into a recession 28 therein. Thus it will be readily understood from an examination of Figs. II and IX that when the connector plug 24 is reversed from the 25 showing in the former figure that the spring contact 26 will not make contact with the screw stud 27, whereby the longer resistance coil will be left in circuit and the heating effect correspondingly reduced.

30 Referring again to the gripping members 9, 10, it is to be noted that the handle or grasp 16 of the latter is immovably secured to an elbowed tang 29 integral therewith by means of a transverse pin 30; and that said 35 handle or grasp 16 is longitudinally recessed at 31 to accommodate a channeled undulate—or “switchback”—reversing cam 32, the purpose whereof will be hereinafter fully explained. On the other hand, the 40 handle or grasp 15 of the gripping member 9 is attached to a channel-section tang 33 by means of the transverse pin 34, said tang in turn being articulated to an offset lug 35 integral with an elbowed extension 35' of 45 the member 9, through the medium of a pin or stud 36. The lug 35 just referred to is flattened at its upper part 37 for co-operative abutment with the adjacent web of the channel-section tang 33, while said tang is 50 normally held in alignment with the member 9 by means of a restraining spring 38 conveniently abutting the back portion 39 of the elbowed extension 35' and coiled around a pin 40 with its outer end engaged 55 through an aperture of the tang web, as shown at 41 in Fig. II. Co-extensive with one flange of the tang 33 is what may be conveniently termed a locking member 42, which is formed with an undulate lower 60 edge 43 and obliquely directed toe 44, both of which are co-operative with the head of the shouldered stud 11, hereinbefore referred to, for purposes that will be hereafter set forth. Intermediate its ends the tang 33 is 65 fashioned to provide spaced ears 45 between

which is pivoted a finger or wiper 46 having a squared end engaging a flat buffer spring 47, bedded in said tang in any convenient manner; and, it will be apparent said spring functions to normally hold the 70 finger or wiper 46 in a position projected, substantially at right-angles to the handle or grasp 9, as best shown in Fig. II.

Transversely-extending indentations 48 are formed in the raised portion 17 of the 75 gripping member 9, while the prongs of the companion forked member 10 are notched as at 49 in correspondence therewith, while it will be observed that said prongs normally 80 repose in the troughed flanges 18 hereinbefore referred to.

The use of my novel hair waving device may be briefly outlined as follows:

The forked member 10 by virtue of its 85 longitudinal curvature is readily inserted in the hair as close to the scalp as possible and the main member 9 closed down upon it. The hair 50 is thereby engaged between the indentations 48 of the member 9, as well as within the notches 49 of the forked member 10, and gripped in the troughed flanges 18, as best understood from Figs. III and VI. The gripping member 9 is thereupon “shogged” longitudinally relative to the 90 forked member 10 by drawing or collapsing 95 the handle 15 towards handle 16. Incident to the action just referred to the free end 51 of the finger or wiper 46 firstly rides over the channeled reversing cam 32 until it 100 abuts the outer end thereof whereupon continued pressure exerted between the handles 15, 16 causes the finger or wiper 46 to assume the position shown in Fig. IV in opposition to the spring 47. Simultaneously with the 105 movement just set forth the locking member 42 will be rocked outwardly on the pivot pin 36, thereby removing the oblique toe 44 from engagement with the head of the stud 11, while the member 9 will be arcuately moved outwards relative to the forked 110 member 10; or, until the outer end of the slot 13 engages the non-threaded portion 12 of said stud, as clearly illustrated in Fig. IV. Upon release of gripping pressure between the handles or grasps 15, 16 the restraining spring 38 re-acts to snap the undulate lower edge 43, of the locking member 115 42, against the head of the shouldered stud 11 and concurrently swings the grasp 15 back into alignment with the member 9, as clearly shown in Fig. V; and, simultaneously the finger or wiper 46 will be returned to normal position under the action of the spring 47 as aforesaid, with its free end 51 advanced forwardly over the high point of the reversing cam 32. Incidentally, it is noteworthy at this point that the handle or grasp 15 of the main member 9, with its forward extension 42 abutting the head of the stud 11, serves to lock said handle or grasp in 120 125 130

aligned position until ready for the succeeding operation. As a result of the movements above outlined the hair 50 will be dragged along in the troughed flanges 18 and take 5 an angular position relative to the raised portion 17 so that the hair is pressed to the curved section of said portion 17, and at the same time retrovertedly curved at opposite sides by co-operation of the forked member 10 with the troughed flanges 18. The members 9, 10 are maintained in the described position for a sufficient period of time to give the necessary set to the hair 50; whereupon 15 a similar sequence of operations as between said members 9, 10 is effected, except that the member 9 is arcuately shogged in a reverse direction through engagement of the finger tip 51 with the inner end of the channeled reversing cam 32, as will be readily understood from the above disclosure without further elaboration herein.

By virtue of providing the compound heating element 19 with a shunt or tap 52—Fig. IX—under control of the spring contact 26, I am enabled to apply different "heats" to the hair 50, and by reason of the high conductivity of the metal from which the members 9, 10 are made, it will be readily understood the heat application takes 30 place in a prompt and efficient manner, irrespective of whether it be of "high" or "low" thermogenic capacity.

Furthermore, it will be apparent, that by reversing the "shog" of the member 9 in 35 the manner described in successive applications of the device, I am able to produce artistic hair waves having uniform undulations devoid of unsightly "kinks" with incidental production of an esthetic coiffure.

Finally, while I have shown and described one practical embodiment of my invention for the purpose of clear disclosure, it is manifest that many changes may be effected in the details of construction, form and arrangement of the several parts, without departing from the scope thereof or sacrificing any of its obvious advantages. Accordingly, the right is hereby reserved to make all such changes as are fairly circumscribed 45 by reasonable interpretation accorded the appended claims.

Having thus described my invention, I claim:

1. In a hair waving device comprising 55 longitudinally curved and transversely notched opposing grip members each with handles, the combination of a cam-actuated shifter member mechanism operable by additional movement applied to one of the 60 handles to planaly shog said members relatively to one another.

2. In a hair waving device comprising longitudinally curved and transversely notched opposing grip members each with 65 handles, the combination of a cam-actuated

shifter finger mechanism operable by super-normal grasp on one of the handles to planaly shog one of said members alternately in reverse directions relative to the other.

70

3. In a hair waving device comprising longitudinally curved and transversely notched grip members, the combination of a handle articulated to one of said members, and a cam-actuated shifter member operable by the articulated handle whereby one of said members may be planaly shogged relative to the other.

75

4. In a hair waving device comprising longitudinally curved and transversely notched grip members, one of which is provided with an articulated handle, the combination of a cam-actuating reversing member mechanism operable by the articulated handle to alternately shog the associated grip member in reverse directions along the other member.

80

5. In a hair waving device comprising a transversely indented member, a co-extensive handle articulated thereto, and a similarly notched opposing forked member having a rigid grasp, the combination of a cam-actuated shifter member operable upon super-normal movement of the articulated handle to shog the first mentioned member planaly over the forked member.

90

6. In a hair waving device comprising a transversely indented member, a co-extensive handle articulated thereto, and a similarly notched opposing forked member having a rigid grasp, the combination of cam-actuated mechanism operable by collapse of the articulated handle to alternately shog the indented member in reverse directions relative to the forked member.

100

7. In a hair waving device the combination of a longitudinally curved and transversely notched grip member, a co-extensive handle articulated thereto, a similarly notched opposing fork member having a rigid grasp, and cam-actuated reversing mechanism operable by super-normal pressure applied to the articulated handle to shog the first mentioned member slidably over the forked member.

110

8. In a hair waving device the combination of a longitudinally curved and transversely notched grip member, a co-extensive handle articulated thereto, a similarly notched opposing fork member having a rigid grasp, and a cam-actuated shifter member operable by the articulated handle to arcuately slide the indented member in reverse directions over the forked member.

120

9. In a hair waving device the combination of a longitudinally curved transversely indented grip member having co-extensive troughed flanges, a co-extensive handle articulated to said member, a similarly notched opposing fork member having a rigid grasp,

125

130

5 said fork member being adapted to engage the troughed flanges, and a cam-actuated shifter member operable by the articulated handle to clampingly shog the first mentioned member over the forked member.

10. In a hair waving device the combination of a longitudinally curved transversely indented grip member having co-extensive troughed flanges, a co-extensive handle articulated to said member, a similarly notched opposing fork member having a rigid grasp, said fork member being adapted to engage the troughed flanges, a cam-actuated shifter member pivoted in and operable by the articulated handle to clampingly shog the first mentioned member relative to the forked member, and means normally holding the device in either shogged position.

11. In a hair waving device the combination of a longitudinally-curved transversely-indented member with a co-extensive articulated handle; a co-operative complementarily notched opposing member with a rigid handle, the latter member being pivoted to 25 the first member with capacity for longitudinal movement; and cam-actuated shifter mechanism, operative by super-normal inward closure of the articulated handle, effective to alternately shog the first mentioned member in reverse directions.

12. In a hair waving device the combination of opposed longitudinally-curved transversely-indented grip members inter-pivoted for scissor-like action and having capacity 35 for limited relative reciprocation, co-extensive handles for manipulating the members with one of said handles articulated and the other rigid, and cam-actuated shifter means operative by super-normal inward pressure exerted upon the articulated handle to shog 40 one of said members alternately in opposite directions.

13. In a hair waving device the combination of a longitudinally-curved transversely-indented member having co-extensive troughed flanges and a co-extensive articulated handle; an opposing complementarily-notched fork member having a rigid handle; said members being inter-pivoted with 50 capacity for limited relative longitudinal movement; a reversing cam race in the handle of the fork member, and a spring influenced finger pivoted in the articulated-handle co-operative with the cam race to effect longitudinal shog of the first mentioned member upon super-normal inward pressure exerted against said articulated-handle.

14. In a hair waving device the combination of a longitudinally-curved transversely-indented member having co-extensive troughed flanges and a spring influenced co-extensive articulated-handle; an opposing complementarily notched fork member having a rigid handle; said members being in-

70 ter-pivoted with capacity for limited relative longitudinal movement; an undulate cam race in the handle of the fork member; and a spring influenced finger pivoted in the articulated handle co-operative with the cam race to effect longitudinal shog of the first mentioned member upon super-normal movement of said articulated-handle.

15. A hair waving device comprising a longitudinally-curved transversely-indented member having co-extensive troughed flanges and a spring influenced articulated-handle; an opposing complementarily notched fork member having a rigid handle; said members being inter-pivoted with capacity for 80 limited relative longitudinal movement; an undulate cam race in the handle of the fork member; and a spring influenced finger pivoted in the articulated-handle and normally projecting outwardly at substantially 85 right angles to the axis thereof, the free end of the finger being co-operative with the cam race aforesaid to effect longitudinal shog of the first mentioned member upon super-normal pressure applied to said articulated-handle.

16. A hair waving device comprising a longitudinally-curved transversely-indented member having co-extensive troughed flanges and a spring influenced articulated-handle; 95 an opposing complementarily notched fork member having a rigid handle; said members being inter-pivoted with capacity for limited relative longitudinal movement; an undulate cam race in the handle of the fork member; a spring influenced finger pivoted in the articulated-handle and normally projecting outwardly at substantially right angles to the axis thereof, the free end of the finger being co-operative with the cam race aforesaid to effect longitudinal shog of the first mentioned member, and means to restrain 100 the members in either shogged position.

17. A hair waving device comprising a longitudinally-curved transversely-indented member having co-extensive troughed flanges and a spring influenced articulated handle; an opposing complementarily notched fork member having a rigid handle; said members being inter-pivoted with capacity for 110 limited relative longitudinal movement; an undulate cam race in the handle of the fork member; a spring influenced finger pivoted in the articulated-handle and normally projecting outwardly at substantially right angles to the axis thereof, the free end of the finger being co-operative with the cam race aforesaid to effect longitudinal shog 115 of the first mentioned member, and an extension of the articulated-handle engageable with the pivot of the opposing members to lock the device in either shogged position.

18. A hair waving device comprising a longitudinally-curved transversely-indented member having co-extensive troughed flanges 120

- and a spring influenced articulated-handle; an opposing complementarily notched fork member having a rigid handle; said members being inter-pivoted with capacity for limited 5 relative longitudinal movement; an undulate channel race in the handle of the fork member; a spring influenced trigger pivoted in the articulated-handle and normally projecting outwardly at substantially right angles 10 to the axis thereof, the free end of the trigger being co-operative with the race aforesaid to effect longitudinal shog of the first mentioned member; and an extension of the articulated-handle tang having an undulate 15 inner edge and oblique toe, respectively, engageable with the pivot of the opposed members to lock the device in either shogged position.
19. In a hair waving device the combination 20 of co-operative longitudinally curved transversely-indented members one of which has an articulated grasp and the other a rigid grasp, said members being inter-pivot-
- ed with capacity for lengthwise shog, shifter means including a reversing cam race in the 25 rigid grasp, and a co-operative spring influenced finger pivoted in and under control of the articulate grasp portion aforesaid.
20. In a hair waving device comprising co-operative longitudinally-curved transversely-indented members inter-pivoted with capacity for lengthwise shog, the combination 30 of a shifter means including a reversing cam race, a cooperative spring influenced finger pivoted in and under control of an 35 articulate portion of one of the members aforesaid, and said articulate portion having an irregularly configured extension engageable with the pivot of the aforesaid members to arrest the same at their limits of lengthwise shog.

In testimony whereof, I have hereunto signed my name at Masontown, Pennsylvania, this 16th day of November, 1925.

OLIVER S. WRIGHT.
